US00D974047S

(12) **United States Design Patent** (10) Patent No.: **US D974,047 S**
(45) Date of Patent: ** Jan. 3, 2023

(54) **MINI ROLLER**

(71) Applicant: **The Sherwin-Williams Company**,
Cleveland, OH (US)

(72) Inventors: **Charles T. Buckel, Jr.**, Warrensville
Heights, OH (US); **Michael C.**
Lambertson, Jr., Warrensville Heights,
OH (US); **Connie M. McKinney**,
Cleveland, OH (US); **William**
Pavilonis, Cleveland, OH (US)

(73) Assignee: **The Sherwin-Williams Company**,
Cleveland, OH (US)

(**) Term: **15 Years**

(21) Appl. No.: **29/784,104**

(22) Filed: **May 18, 2021**

Related U.S. Application Data

(62) Division of application No. 29/673,403, filed on Dec.
14, 2018, now Pat. No. Des. 921,367.

(57) **CLAIM**

The ornamental design for a mini roller, as shown and described.

DESCRIPTION

FIG. 1 is a perspective view of an embodiment of a mini roller showing our new design;
FIG. 2 is a first side view thereof;
FIG. 3 is a second side view thereof;
FIG. 4 is a bottom side view thereof;
FIG. 5 is a top side view thereof;
FIG. 6 is a back view thereof; and,
FIG. 7 is a front view thereof.
The broken lines illustrate portions of a mini roller that form no part of the claimed design.

1 Claim, 5 Drawing Sheets
